Charles D. Hall

United States Patent Office.

CHARLES D. HALL, OF BRISTOL, CONNECTICUT, ASSIGNOR TO "THE BRISTOL BRASS AND CLOCK COMPANY," OF SAME PLACE.

Design No. 4,348, dated September 13, 1870.

DESIGN FOR HANDLES OF SPOONS, FORKS, &c.

The Schedule referred to in these Letters Patent and making part of the same.

To all whom it may concern:

Be it known that I, CHARLES D. HALL, of Bristol, in the county of Hartford and State of Connecticut, have invented and produced a new and original Design for Handles for Knives, Forks, and Spoons, of which the following, taken in connection with the accompanying drawing, is a specification.

Figure 1 represents a face view of a fork or spoon-handle, in part, made in accordance with my new design, and

Figure 2, a transverse section of the same, through the line $x x$ in fig. 1.

Similar letters of reference indicate corresponding parts.

The contour of the handle, which is shown in fig. 1, presents, at the junction of the head C with the shank A, a circular swell, B B, or, in other words, the outline on each side presents, in that part of the handle, an arc-formed projection, the arcs on the two sides being concentric, or nearly so, with each other.

From the bottom of the circular swell the shank A tapers slightly downward, and from the top of the said swell the head increases in width, with a hollow curvature on each side as far as a point, s, whence the width begins to diminish abruptly, and the contour takes the form of lines which are nearly straight, having a very slight outward curvature, but no decided protuberances.

The face and back are similarly ornamented, as follows, in bas-relief.

Threads or fillets, b b, extend continuously along the shank A, the swell B, and the sides of the head, and close within these fillets, and in parallel courses thereto, are finer bas-relief threads or beads c c, which, however, are not extended below or beyond the swell B, and which, as well as the outer fillets or border threads b b, are intercepted just below the points s s by ornaments d d, having scroll-like terminations, e e, both of which face outward.

Arranged as a pendant from the backs of these ornamental figures d d, is a fanciful device, consisting of a double spear-shaped bar or drop, f f, with two petals, g g, arranged on either side of it, and made to extend both above and below a cross-band, h.

The swell B contains within it an ornament resembling a letter H, of fanciful pattern, on a threaded base, and crossed by a bar or device, k, running in direction of the length of the handle up its center, and having scroll ends, with projecting barbs or spear-like terminations, m m, between them, the whole forming an ornamental configuration, which has a like appearance both when the handle is in an upright and in an inverted position.

I claim as my invention—

The design for a spoon or other handle, as shown and described.

CHAS. D. HALL.
